(57) **CLAIM**

The ornamental design for an escalator handrail entry, as shown and described.

DESCRIPTION

FIG. 1 is a perspective view of an escalator showing an inventive design for handrail entries as shown in full lines, in four locations. Portions of the escalator shown in broken lines form no part of the design;

FIG. 2 is a view taken along the line 2—2 of FIG. 1 of the handrail entry;

FIG. 3 is a view similar to FIG. 2 showing the opposite side thereof;

FIG. 4 is a view from the front thereof;

FIG. 5 is a view from the right side thereof;

FIG. 6 is a view from the top thereof; and,

FIG. 7 is a view from the left side thereof.
